CLAIM

I claim the ornamental design for a coin segregation device, as shown and described.

DESCRIPTION

FIG. 1 is a front perspective view of the coin segregation device, showing the new design;
FIG. 2 is a front elevational view of FIG. 1;
FIG. 3 is a rear elevational view of FIG. 1;
FIG. 4 is a right side elevational view of FIG. 1;
FIG. 5 is a left side elevational view of FIG. 1;
FIG. 6 is a top plan view of FIG. 1; and,
FIG. 7 is a bottom plan view of FIG. 1.
